(57) **CLAIM**

The ornamental design for a cutting insert, as shown and described.

DESCRIPTION

FIG. 1 is a perspective view of an alternate cutting insert showing a modified embodiment of our new design;

FIG. 2 is a top plan view of the cutting insert of FIG. 1, with the bottom view being a mirror image thereof; and, FIG. 3 is a side view thereof, with the remaining side views being a mirror image thereof.

The broken line showing is for illustrative purposes only and forms no part of the claimed design.
